MACHINE FOR ATTACHING SOLES TO SHOES

Joseph G. Herbers and Benjamin W. Freeman,
Cincinnati, Ohio

Application June 7, 1929, Serial No. 369,039

49 Claims. (Cl. 12—37)

This invention relates to machines adapted particularly for attaching soles to shoes and more particularly by cement.

In the manufacture of boots and shoes in accordance with one of the well known processes, the outsole is attached to the upper by means of cement having usually a nitro-cellulose base. The upper on the last is placed on a shoe support having a co-operating inflatable sole-engaging pad and provided with a work holder or clamp serving to hold the shoe and the sole thereon against the pad; this pad is inflated or otherwise acted upon so as to press the sole against the upper. After an interval sufficient to permit setting of the cement, the pad is deflated or otherwise manipulated to release its pressure on the sole, in order to permit removal thereof. While the process as heretofore practiced has been supplemented or carried on in part by machinery, this machinery has been in the main elemental in form and arrangement and almost wholly hand operated, thereby requiring not only skillful manipulation, but also considerable time.

One of the objects of this invention, therefore, is to provide a machine of the character described whereby the operations may be more conveniently, expeditiously and effectively performed.

Another object is to provide a machine of the character described, in which the operations are almost wholly automatic.

Another object is to provide a machine of the character described, which is simple in construction, effective in its action and economical to manufacture.

Further objects will appear from the detail description, taken in connection with the accompanying drawings, in which will be described an illustrated embodiment of this invention; it is to be understood, however, that this invention is susceptible of various embodiments within the scope of the appended claims.

In the accompanying drawings:

Figure 1 is a side elevation, partly in section, of a machine embodying this invention;

Figure 2 is a front elevation;

Figure 3 is a detail of the carrier driving mechanism;

Figure 4 is an elevation of a part of the carrier and one of the work supports;

Figure 5 is a detail showing the mounting of a support on the carrier;

Figure 6 is a section on line 6—6, Figure 5;

Figure 7 is a section on the line 7—7, Figure 4; Figure 8 is a section on the line 8—8, Figure 1, showing parts in elevation;

Figure 9 is a section on the line 9—9, Figure 8;

Figure 10 is a detail plan of one of the carriers, showing the air-controlled valve and other mechanisms;

Figure 11 is a side elevation of Figure 10;

Figure 12 is a section of the air-controlled valve on the line 12—12 of Figure 10;

Figure 13 is a perspective showing the mechanism for operating the air valve;

Figure 14 is a detail plan showing mechanism for retracting and projecting the supports;

Figure 15 is a section on the line 15—15, Figure 14, showing parts in elevation;

Figures 16 and 17 are views of the air-controlled valve for the retracting and projecting cylinder;

Figure 18 is a side elevation showing a single treadle control; and

Figure 19 is a detail perspective view of Figure 18.

Generally stated, in accordance with this invention, a carrier is provided which is arranged or mounted for movement relatively or with respect to a station or stand. A work support is mounted on this carrier for movement between work-receiving and work-setting positions. In order to place this work support in work-receiving position, it is moved adjacent the station or stand, in which position the work can be removed and replaced; the support is then moved to work-setting position, back on or against the carrier. In the illustrated embodiment of this invention, a series of these work supports is arranged on the periphery or rim of a wheel which moves vertically past the station or stand. These work supports are pivoted in alternating relation on opposite sides of the rim so as to enable them to be successively swung laterally adjacent the stand, first from one side and then from the other side.

The carrier or wheel is driven mechanically, and suitable clutch or stop mechanism is provided for arresting the carrier with the work support opposite or adjacent the stand. Mechanism is also provided, which is automatic in its action, to swing the work support as it comes opposite the stand to work-receiving position adjacent the stand, in order to enable the operator to remove and replace the work; thereafter mechanism operates to swing the support back against the carrier or wheel, which then proceeds to cause the work support with the work

thereon to travel onward while the next work support on the opposite side of the carrier is moved to position and proceeded with as before. Suitable means is provided for locking the work support in position on the carrier or wheel. This locking means is so constructed that when the work support approaches the stand, the support will become unlocked to permit it to be moved adjacent the stand; while when the work support is moved back against the carrier and the latter travels onward, this locking means is again engaged in order to positively secure the work support with the work thereon in position.

Each work support is provided with suitable work holding means, which may be generally of the character previously referred to and comprising an inflatable pad and a work holder or clamp; this pad being arranged for inflation and deflation, and the work holder or clamp being arranged for engagement and release. In accordance with this invention, however, means is provided whereby the release and reengagement of the shoe are effected automatically or at least semi-automatically. For this purpose, means is provided at the station or stand for effecting release and clamping or pressing of the work. In accordance with the illustrated embodiment of this invention, means is provided where upon approach of a given work support to the station or stand, the pad is deflated or otherwise released; and as the support reaches work-receiving position, the clamp is also released. While the support is in work-receiving position, means is provided for again clamping the shoe and inflating or otherwise rendering the pad effective to apply pressure to the work. This inflating means is under the control of the operator in work-receiving position, so that the operation of applying pressure to the work may be effectively controlled. After the work has thus been placed on the work support and clamped, the work support is returned to work-setting position against the carrier or wheel and the latter is started to travel onward in order to permit the cement to set. While the carrier travels onward, the fluid pressure, where employed, is continuously applied to the pad to continuously hold the work under pressure while the cement is setting.

Referring now to the accompanying drawings and more particularly to Figures 1, 2 and 3, 1 designates a carrier which in this particular embodiment is in the form of a wheel mounted for rotation between two brackets or pedestals 2. Arranged close to but in front of the periphery of the carrier is a stand or pedestal 3 whose top is of such height as to be convenient to the operator in front of this stand.

The periphery of the carrier is arranged for engagement by a friction wheel 4 whose shaft 5 has a connected worm gear 6 meshing with a worm 7 whose shaft has a pulley 8 connected by a belt 9 to a suitable motor 10. The elements 4, 5, 6, 7 and 8 are arranged on a suitable frame 11, which is pivoted at 12 on the stand 3 so that this frame may be swung in order to engage and disengage the wheel 4 with the carrier, the movement being, however, so slight that the belt 9 will not slip off the pulley 8.

The frame 11 has an arm 13 in the end of which is suitably clamped a stop pin 14 arranged to engage in one of a series of sockets 15 in the periphery of the carrier 1. The end of the arm 13 is arranged for engagement by the end of a lever 16 pivoted intermediate its ends on the stand 3 and arranged with its other end in the

path of a slide 17 on the stand 3, which slide, as hereinafter described, is reciprocated during the operation of the machine. The engagement of the levers 13 and 17 is effected by an adjustable set screw 18. The stop 14 is actually clamped in a holder 19 pivoted at 20 on the end of the lever and adjusted about that pivot by screws 21. In this way the stop 14 can be adjusted with respect to the sockets 15, which latter, when opposite the bolt, are generally along an arc having the 10 shaft 5 as a center.

Pivoted on opposite sides of the rim of the carrier 1 is a series of work supports 22. These work supports are arranged in alternating relation on opposite sides of the rim so that they can be 15 moved against one or the other side of the stand. The sockets 15 are so arranged that when a given socket is opposite the stop 14, a given work support will be opposite the stand. If at this time the lever 16 is released by the 20 slide 17, the weight of the parts will permit the wheel 4 to swing away from the carrier rim, while the stop 14 will ride upon the periphery until it drops into the socket, thereby stopping the carrier with a given support opposite the stand. 25 When, however, the slide 17 again moves to the left (Figure 3), the stop will be withdrawn from its socket, while the wheel 4 will be swung against the carrier rim so as to move the carrier on.

Referring now to Figures 1, 2, 4, 5 and 6, each 30 support 22 is pivoted by a pin 23 on a bracket 24 attached to or forming a part of the carrier rim. The support is arranged to be swung against the rim, or rather against the bracket 24, a buffer 25 being provided to lessen the shock. In order to 35 lock the support in setting position against the rim, a bolt 26 takes against a shoulder 27 on the support knuckle. This bolt is normally held in locking position by a spring 28 coiled on a pivot 29 for a finger 30 and taking over a pin 31 on the bolt, 40 which pin extends over the finger. This finger 30 projects beyond the rim of the carrier 1, and arranged within the path of the finger is a stop 32 on a bracket 33 mounted on the stand 3. It will be understood that there is a stop 32 on each 45 side of the bracket 33, one for each set of support and locking fingers on each side of the carrier rim.

As each support comes to a position opposite the stand 3, its unlocking finger 30 will engage the 50 stop 32 as this support comes to work-receiving position, so as to unlock the support. As the carrier now comes to rest, by engagement of the stop 14 with the socket 15, the carrier can be moved to a position against the stand to permit removal and 55 replacement of the work, while the bolt 26 rides on the knuckle.

Referring now to Figures 1, 2, 4, 7, 8 and 9, each support comprises a box-like structure having a bottom 34 conforming in a general way to the 60 sole bottom, and within this box-like structure is arranged a pad 35, which in this particular embodiment is of the inflatable type. Against this bag is arranged to be placed a shoe sole and the shoe mounted on a suitable last 36. A clamp is 65 provided for holding the shoe against the bag and to provide an abutment when the latter is inflated. The clamp or holder comprises a head 37 having parts 38 and 39 adjustable therealong and adapted for different sizes of lasts. The head 37 70 is mounted on shanks 40, which may be threaded to receive nuts 41 and which pass through bearings 42 in the work support. Springs 43 encircle the shanks between the support and the head and normally tend to hold the latter in raised posi- 75

tion until stopped by the enlarged bottom ends 44 of these shanks engaging the bottoms of the bearings 42. The lower ends of these shanks are connected by a cross-bar 45, the ends of which 5 straddle the shanks and bear on lugs 46. The ends of this bar are beveled to engage with teeth on latches 47 pivoted on the support and held in engagement by springs 48. These latches are connected by links 49 to arms 50 on a shaft 51 provided with a manipulating handle 52. One of these arms 50 has a laterally directed cam part 53 arranged to engage a corresponding cam part 54 on the stand 3. The cam parts 54 are in duplicate, as will be seen from Figure 7, and each has a shank 55 sliding through the top of the stand 3 and connected by a link 56 with a treadle 57, which is normally held in raised position by a spring 58. Any suitable adjustable stop 59 may be provided to limit the upward movement of the cam parts 20 54.

Assuming that the work clamp is in a position to clamp the work, as shown in Figures 4, 5, 8 and 9, and with the springs 43 under compression and the head 37 held down by engagement of the latches 47 with the ends of the cross-bar 45; as the support is swung against the stand 3, the cam part 53 will engage the cam part 54 so as to rock the shaft 51 and disengage the latches 47, thereby permitting the head 37 to rise under the action of the springs 43. Since, however, the cam part 54 is at this time over the cross-bar 45, upon depression of the treadle 57, the part 54 will engage and depress the cross-bar, carrying the head 37 with it; and as the cam part 53 has been disengaged upon this movement, the latches 47 again become active to engage the ends of the cross-bar 45 and lock the work clamp in the desired position. Upon release of the treadle, the cam part 54 will move underneath the cam part 53, but will, of course, not actuate the same. The latches 47 may be disengaged at any time manually by manipulation of the handle 52.

Referring now to Figures 1, 2, 4, 5 and 8 to 13, a compressed air pipe 60 is connected with a bore 45 in the shaft 61 for the carrier 1 by a suitable coupling 62, which permits rotation of this shaft while maintaining the pipe 60 in sealing engagement with the bore. A pipe 63 leads from the bore in the shaft 61 to a pipe 64 extending along the rim of the carrier. To this pipe 64 is tapped at intervals a series of pipes 65 passing through the swivel pins 23 of the different supports. From hence they connect with an inlet 66 of a valve casing 67 provided with a valve 68. The valve casing is provided with a connection 69 leading to the bag and with a connection 70 leading to a relief valve casing 71. This casing is provided with a valve 72, the tension of whose spring 73 can be controlled by an adjustable abutment collar 74, so as to exhaust to any desired degree. The valve 68 is held on its seat by a spring 75 and is provided with a port 76 adapted to connect the bag connection 69 with either the compressed pipe 66 or with the exhaust or relief connection 70.

The valve 68 has a pinion 77 meshing with a segment 78 on a lever 79, the other end of which travels in the path of a stop 80 on the bracket 33, it being understood that there is a stop 80 on each side of the bracket, one for each series of supports. The lever 79 has its end turned to provide a pin 81, which, when the support is swung against the stand, is arranged to engage with a notch 82 in a head 83 on the end of an arm 84 pivoted on the stand 3 and connected by a link 85 with another treadle 86 also held in raised

position by a spring 87. It will be understood that the head 83 has a notch on each side thereof, one for each series of supports.

When a given support approaches the stand, the end of the lever 79 will, by engagement with the stop 80, shift the valve 68 so as to disconnect the bag from the compressed air supply and connect it with the exhaust or relief valve casing 71. The spring of the relief valve can be adjusted so as to exhaust the air in the bag to any 10 desired limit; and by complete release of pressure on the springs 73, the air may be wholly exhausted. When the support is swung against the stand 3, so as to couple the lever 79 with the arm 84, then by manipulation of the treadle 86 15 the bag may again be connected with the compressed air so as to inflate it to the desired extent. Upon release of the treadle, however, the air may again be exhausted from the bag to the desired degree. The spring 75 will hold the valve 20 78 in any of its adjusted positions, and for convenience, the lever 79 may be arrested by stops 870.

As heretofore described, mechanism is provided for moving the supports against or adjacent 25 to the stand. For this purpose, and mounted upon the stand 3 (Figures 1, 2, 4, 8 and 14 to 17) is a base 88, on which are mounted two heads 89 and 90 for a cylinder 91, which heads are connected by bolts 92. Traveling in this cylinder is a piston 93, the piston rod 94 of which has a cross-head 95 traveling in a guide 96 and having a part 17 which forms the slide heretofore referred to as engaging the lever 16 (Figure 1). The cross-head 95 also has a pair of links 97, each of which 30 35 is pivoted to a block 98 moving in a T-shaped guide 99 and provided with a pin 100 arranged to couple with a slot 101 (Figures 10 and 11) in a plate 102 pivoted between two downwardly extending parts 103 in the support 23 and normally 40 held horizontally against a stop 104 by a spring 105.

Compressed air is supplied to the cylinder by a pipe 106 (Figure 15) and it is distributed by a valve 107 having a port 108 arranged to selectively 45 connect either end of the cylinder with the compressed air. This valve also has ports 109 leading externally of its casing and to the open air, so as to selectively connect either end of the cylinder with the atmosphere. The valve is of 50 the tapered type and is retained on its seat by a spring 110. It is provided with a pinion 111 meshing with an idler 112, which in turn meshes with a segment 113 on a lever 114 pivoted intermediate its ends on the base 88, or rather in the 55 bracket 33 on that base. The other end of the lever is engaged by a spring 115, which holds that end against a stop 116 on the bracket 33.

The end of the lever 114 is slotted to receive a block 117 normally held by springs 118 against 60 the rim of the carrier and in the path of a series of lugs 119, one for each support. The block is connected with an arm 120 of a lever pivoted intermediate its ends on the bracket 33 and having an arm 121 in the path of shoulders 122 and 65 123 of a tappet 124 pivoted on the arm 84 but frictionally held against movement in either of its positions. A hook 125 on the arm 84 is arranged to take under a keeper 126 on the block 117 so that when the arm 84 is depressed, it will 70 be held in depressed position.

With the parts in the position shown in Figure 15, in which the spring 115 will hold the lever 114 against the stop 116, the valve 107 will be held in a position to connect the right end 75

of the cylinder with the compressed air, thereby holding the piston in position to engage the wheel 4 with the carrier rim (Figure 1). The blocks 98 (Figure 14) are at this time held in position 5 ready to couple with the slots 101 in the plates 102. As now a support approaches the stand, a lug 119 corresponding to that support will engage the block 117, thereby moving the left-hand of the lever 114 (Figure 15) down against the tension of the spring 115. This will shift the valve 107 so as to connect the right end of the cylinder with the exhaust and the left end of the cylinder with the compressed air supply. As the plate 102 of the support has at this time coupled 10 with a pin 100, the movement of the piston 93 to the right will swing the support against the stand 3. The initial movement of the piston, however, releases the pressure of the slide 17 on the lever 16 (Figure 1), thereby causing the wheel 20 4 to disengage the carrier rim while the stop 14 enters its appropriate socket to arrest the carrier. When the support is to be again projected, the operator can depress the treadle 86, thereby causing the tappet 124 to engage the arm 121 so 25 as to withdraw the block 117 from underneath the lug 119. This will cause the spring 115 to again shift the lever 114 back to the position shown in Figure 15, so as to shift the valve and reverse the movement of the piston in order to 30 again project the work support against the carrier, which then travels on.

Arranged on each side of the stand 3 is an arm 127 provided with a roll 128 in the path of one of the lugs 103. The arms 127 can be mounted 35 on a single shaft 129 so as to be under the action of a single spring 130 connecting the arm with an anchor 131 on the stand and serving to hold the roll 128 in the path of the lug 103. The purpose of this roll is to hold each support against 40 its carrier after the plate 102 has uncoupled from the pin 100 so that this support will be held in place against the carrier rim until after the locking key 26 has again become effective. The pivotal mounting of the plate 102 enables the latter 45 to become disengaged from the pin 100, for upon downward movement of the support, the plate will slide and pivot so as to uncouple from the pin.

Referring now to Figures 18 and 19, the two treadles 57 and 86 have been combined into a 50 single treadle 150, the links 56 and 85, which connect, respectively, to the cam actuator 54—55 and the arm 84, have at their lower ends tubular parts 151 and 152 having springs 153 and 154, respectively. Each tubular part has working 55 therein a shank 155 provided with a head 156. Each shank has a block 157 provided with a hook 158 adapted to engage a corresponding hook 159 on the treadle 150. The treadle travels between upstanding parts 160 of a bracket 161, and the 60 blocks also move between these parts. These upstanding parts are slotted to receive the ends 162 while springs 163 serve to hold the teeth 158—159 in engagement. Cams 164 and 165 are 65 arranged to engage the ends 162 and disengage the teeth. It will be noted that the springs 153 and 154 are of different lengths and that the cams 164 and 165 are of different heights.

Upon depression of the treadle 150, the links 56 and 87 will be depressed, carrying with them 70 the connected parts. As, however, the blocks 157 travel downwardly, the cam 164 will release the link 56 before the cam 165 will release the link 87. Upon disengagement of any set of hooks 158 and 159, however, the springs 153, 154 serve 75 to permit the hooks 158 to return.

As the operation of the various mechanisms has been described, it will only be necessary at this point to give a résumé of the operations generally. Assuming that the carrier travels in the direction of the arrow, Figure 1, let us start 5 with the work as it approaches the stand or station 3. At this time the shoe will be clamped between the work clamp and the inflated pad, the work clamp being locked in position by the latches 47 and the pad being under the action of 10 the compressed air, in view of the fact that the valve 68 (Figure 10) is in a position to connect the intake pipe 66 with the bag connection 69 (Figure 12). At this time, moreover, the supports are against the rim of the carrier and are 15 individually locked by the bolts 26. Assuming now that the work is ready to be removed from any given support as it approaches the stand or station 3, the operations will be briefly as follows:

The lever 79 engaging with the stop 80 will 20 shift the valve 68 (Figure 12) to a position so as to connect the bag with the exhaust or relief valve casing 71. The stop 80 may be located in a sufficiently advanced position as to 25 cause the bag to become exhausted to the desired extent when the support moves to work-removing position against the stand. The finger 30 will now engage the stop 32 (Figure 5), thereby unlocking the support. At this point 30 the lug 119 will engage the block 117 so as to shift the lever 114 in order to connect the left end of the cylinder with the compressed air (Figure 15), thereby causing the piston to move to the right. The initial movement of the piston 35 will retract the slide 17 so as to cause the wheel 4 to disengage the carrier rim and the stop pin 14 to engage its socket (Figure 1) so as to stop further rotation of the carrier. At this time the plate 102 will have coupled with 40 the pin 100 (Figure 14) so that the support is moved against the stand. In the latter part of this movement, the cam parts 53 and 54 will engage (Figure 8) so as to release the work 45 clamp.

The shoe can now be removed and another one placed in position. After the shoe has been placed in position with the sole on the pad, the operator can either depress the treadle 57 to the desired extent to apply the work clamp 37 or move the 50 single treadle 150 to preliminarily clamp the shoe. The operator can then connect the pad with the compressed air so as to inflate it, and this can be accomplished by either the depression of the treadle 86 or further depression of the single 55 treadle 150. It will be noted that the preliminary part of the movement of the arm 84 (Figure 15) effects the admission of air to the pad, while the final depression causes the tappet 124 to engage the arm 121 and withdraw the block 60 117. Upon final depression of either the treadle 86 or 150, the valve 107 will again be shifted by the spring 115 acting through the lever 114 to again connect the right end of the cylinder with the compressed air supply. The result is, 65 therefore, that the support will be projected back against the carrier while the slide 17 will, through the connections previously described, withdraw the stop 14 from the socket in the rim and throw the wheel 4 against the rim so as to 70 drive it onward. During this onward movement, the support is pressed against the carrier by the roll 128 as the carrier becomes disconnected from the projecting and retracting mechanism, and this support is finally again locked by its bolt 75

26. The support can, therefore, travel onward until it again reaches the stand or station.

It is sometimes desirable to move a support onward without inflating the pad. It is for this purpose that the adjustable tappet 124 is provided. When this tappet is in the position shown in full lines, Figure 15, the operations will be as heretofore described. When, however, this tappet is placed in dotted position, then the initial depression of the arm 84 will retract the block 117. Now, the valve is so constructed and connected that a definite movement is required before the pad is connected to the compressed air supply. The construction is, therefore, such that with the tappet in dotted position (Figure 15), the movement of the arm to retract the block 117 out of the path of the lug 119 is accomplished before the valve can be moved to connect the compressed air supply with the pad. The result is, therefore, that the support will be returned against the carrier with the valve 68 in exhaust position.

It is desirable that the mechanism be under complete control at all times, so that a shoe may be released while the support is in position adjacent the stand and even after the shoe has been clamped to the inflated pad. This is readily accomplished in accordance with this invention; for after the shoe has been clamped and upon depression of the treadle to admit air to the bag, upon release of the treadle the air will become exhausted. Furthermore, the clamp can also be released at any time by manipulation of the handle 52 (Figure 4) provided for that purpose. The mechanism is, therefore, under complete control of the operator.

By arrangement of the supports on the carrier in the manner described, these supports are brought to convenient position where the work can be readily manipulated by the operator with a minimum of exertion and with a maximum of efficiency. Not only are his hands left entirely free, but the mechanism is always under complete control. The arrangement of the supports on opposite sides of the carrier to swing alternately into position, not only facilitates the operation, but enables right and left shoes to be handled with convenience and expedition. The space factor of the machine is also high and favorable.

It will be particularly noted that when a shoe is on its support with the work clamp engaged and with the pad inflated, the shoe bottom is under pressure, which, in addition to performing the function of pressing the sole on the shoe (where the attachment is by cement), the sole and the shoe bottom as a whole is shaped to the last. This shaping or pressing function is useful in many cases, even where the sole is not attached by cement or where the machine is employed for a purely shaping or bottom leveling operation.

In the particular embodiment illustrated and described, the expandible pad is in the form of an air bag, which may be inflated by the admission of air pressure and deflated by the exhaust or release of the air therefrom. It is, however, to be understood that any other fluid or liquid may be used for inflating this pad. It will, furthermore, be understood that this pad may be simply of a yielding character, being constructed for that purpose in any suitable manner, as by filling it with any desired material to secure a yielding structure or even with air or a liquid, or by constructing it of a material such as spongy

rubber. Where inflation and deflation are not resorted to, but the pad simply has a yielding structure, then the clamping of the work between the work clamp and the pad is accomplished by depression of the clamp and its locking in position by the mechanism described; in such a case the inflating mechanism may, of course, be entirely dispensed with.

It will, furthermore, be understood that while the invention is particularly applicable to the operations of attaching an outsole to a shoe by means of cement, it will be understood that it has various applications, particularly to the shoe machine art, which will be understood by those skilled in the art. It is, furthermore, to be understood that certain features and sub-combinations are of utility and may be employed without reference to other features and sub-combinations; that is contemplated by and is within the scope of the appended claims. It is furthermore obvious that various changes may be made in details, within the scope of the appended claims, without departing from the spirit of this invention. It is, therefore, to be understood that this invention is not to be limited to the specific details shown and/or described.

Having thus described the invention, what is claimed is:

1. A machine of the character described, comprising, a carrier, and a work support permanently mounted on said carrier and having means for sustaining a shoe and its sole in cooperative setting relation, said work support and said means being movable as a unit relative to said carrier between work-receiving and work-setting positions.

2. A machine of the character described, comprising, a movable carrier, a work-support permanently mounted on said carrier for movement between work-receiving and work-setting positions, and means for sustaining a shoe and its sole in cooperative setting relation on said support, and means for moving said support and sustaining means as a unit relative to said carrier.

3. A machine of the character described, comprising, a stand arranged in a work-receiving position, a carrier mounted for movement with respect to said stand, and a work support permanently mounted on said carrier and for movement thereon adjacent said stand, said work support having means thereon for sustaining a shoe and its sole in cooperative setting relation.

4. A machine of the character described, comprising, a stand arranged in a work-receiving position, a carrier mounted for movement with respect to said stand, a work support permanently mounted on said carrier and for movement thereon adjacent said stand, said work support having means thereon for sustaining a shoe and its sole in cooperative setting relation, and means arranged adjacent said stand for moving said support.

5. A machine of the character described, comprising, a carrier arranged for movement relative to a work-receiving station, a work support permanently mounted on said carrier for movement into work-setting position, said work support having means thereon for sustaining a shoe and its sole in cooperative setting relation, and means for moving said support with its sustaining means as a unit to work-receiving position when it reaches said station.

6. A machine of the character described, comprising, a carrier arranged for movement relative to a work-receiving station, a work support per-

manently mounted on said carrier for movement into work-setting position, said work support having means thereon for sustaining a shoe and its sole in cooperative setting relation, means for stopping said carrier when said support reaches said station, and means for moving said support relative to said carrier and into position adjacent said station.

7. A machine of the character described, comprising operating mechanism, a carrier arranged for movement relative to said mechanism, and a work support permanently mounted on said carrier for movement relative thereto into position to co-operate with said mechanism, said work support having means thereon for sustaining a shoe and its sole in cooperative setting relation.

8. A machine of the character described, comprising, operating mechanism, a carrier arranged for movement relative to said mechanism, a work support mounted for movement on said carrier, said work support having means thereon and movable therewith for sustaining a shoe and its sole in cooperative setting relation, and means for coupling said support with and when it reaches said mechanism.

9. A machine of the character described, comprising, operating mechanism, a carrier arranged for movement relative to said mechanism, and a work support mounted for movement on said carrier, said work support having means thereon for sustaining a shoe and its sole in cooperative setting relation, said operating mechanism having means adapted to couple with and move said support.

10. A machine of the character described, comprising, operating mechanism, a carrier arranged for movement relative to said mechanism, and a work support mounted for movement on said carrier to work-receiving position, said work support having means thereon for sustaining a shoe and its sole in cooperative setting relation, said operating mechanism having means adapted to couple with and move said support to work-receiving position.

11. A machine of the character described, comprising, operating mechanism, a carrier arranged for movement relative to said mechanism, and a work support mounted for movement on said carrier to work-setting position, said work support having means thereon for sustaining a shoe and its sole in cooperative setting relation, said operating mechanism having means adapted to couple with and move said support to work-setting position.

12. A machine of the character described, comprising, operating mechanism, a carrier arranged for movement relative to said mechanism, and a work support mounted for movement on said carrier to work-receiving and work-setting positions, said work support having means thereon for sustaining a shoe and its sole in cooperative setting relation, said operating mechanism having means adapted to couple with and move said support to work-receiving and work-setting positions.

13. A machine of the character described, comprising, operating mechanism, a carrier arranged for movement relative to said mechanism, means for moving said carrier, a work support permanently mounted for relative movement on said carrier, said work support having means thereon for sustaining a shoe and its sole in cooperative setting relation, and means for stopping said carrier with said support adjacent said operating mechanism.

14. A machine of the character described, comprising operating mechanism, a carrier arranged

for movement relative to said mechanism, means for moving said carrier, a work-support mounted for movement on said carrier, said work support having means thereon for sustaining a shoe and its sole in cooperative setting relation, means for coupling said support with said operating mechanism, and means for stopping said carrier upon such coupling.

15. A machine of the character described, comprising, operating mechanism, a carrier arranged for movement relative to said mechanism, means for moving said carrier, a work support mounted for movement on said carrier, said work support having means thereon for sustaining a shoe and its sole in cooperative setting relation, and means for stopping said carrier with said support adjacent said operating mechanism, said mechanism having means adapted to couple with and move said support.

16. A machine of the character described, comprising, a carrier arranged for movement relative to a station, a work support mounted for movement on said carrier, said work support having means thereon and movable therewith for sustaining a shoe and its sole in cooperative setting relation, means for locking said support on said carrier, and means for unlocking said support when it reaches said station.

17. A machine of the character described, comprising, a carrier arranged for movement relative to a station, a work support mounted for movement on said carrier, said work support having means thereon and movable therewith for sustaining a shoe and its sole in cooperative setting relation, and means operating independently of said sustaining means for locking said support when it leaves said station.

18. A machine of the character described, comprising, a carrier arranged for movement relative to a station, a work support mounted for movement on said carrier, said work support having means thereon for sustaining a shoe and its sole in cooperative setting relation, means for locking said support on said carrier, means for disengaging said locking means when said support approaches said station, and means for engaging said locking means when said support leaves said station.

19. A machine of the character described, comprising, operating mechanism, a carrier arranged for movement relative to said mechanism, means for moving said carrier, a work support mounted for movement on said carrier, said work support having means thereon for sustaining a shoe and its sole in cooperative relation, means for locking said support on said carrier, means for disengaging said locking means when said support approaches said operating mechanism, and means for stopping said carrier with said support adjacent said mechanism.

20. A machine of the character described, comprising, operating mechanism, a carrier arranged for movement relative to said mechanism, means for moving said carrier, a work support mounted for movement on said carrier, said work support having means thereon for sustaining a shoe and its sole in cooperative relation, means for locking said support on said carrier, means for disengaging said locking means when said support approaches said operating mechanism, and means for coupling said mechanism with and to move said support.

21. A machine of the character described, comprising, operating mechanism, a carrier arranged for movement relative to said mechanism, means

for moving said carrier, a work support mounted for movement on said carrier, said work support having means thereon for sustaining a shoe and its sole in cooperative setting relation, means for locking said support on said carrier, means for disengaging said locking means when said support approaches said mechanism, means for stopping said carrier with said support adjacent said mechanism, and means for coupling said mechanism with and to move said support.

22. A machine of the character described, comprising, a carrier arranged for movement relative to a station, means for moving said carrier, a work support mounted on said carrier, means for holding a shoe and its sole in cooperative setting relation on said support, means for moving said support on said carrier and adjacent said station, and means for releasing said work holding means when the support reaches said station.

23. A machine of the character described, comprising, a carrier arranged for movement relative to a station, means for moving said carrier, a work support mounted on said carrier, means for holding a shoe and its sole in cooperative setting relation on said support, means for stopping said carrier when the support reaches said station, means for moving said support on said carrier and adjacent said station, and means for releasing said work holding means at said station.

24. A machine of the character described, comprising, a carrier arranged for movement relative to a station, a work support mounted for movement on said carrier, means for holding a shoe and its sole in cooperative setting relation on said support, means for moving said support on said carrier and adjacent said station, and means for releasing said work holding means when the support reaches said station.

25. A machine of the character described, comprising, a carrier arranged for movement relative to a station, a work support mounted for movement on said carrier, means for holding a shoe and its sole in cooperative setting relation on said support, means for moving said support and said holding means as a unit when at said station, and means for releasing said work holding means.

26. A machine of the character described, comprising, a carrier arranged for movement relative to a station, a work support mounted for movement on said carrier, means for holding a shoe and its sole in cooperative setting relation on said support, means for stopping said support adjacent said station, means for moving said support, and means for releasing said work holding means.

27. A machine of the character described, comprising, a carrier arranged for movement relative to a station, means for moving said carrier, a shoe support mounted for movement on said carrier, an inflatable sole-engaging pad on said support, and means for deflating said pad when the support is moving adjacent said station.

28. A machine of the character described, comprising, a carrier arranged for movement relative to a station, means for moving said carrier, a shoe support permanently mounted on said carrier, a sole-engaging pad on said support, means for effecting release of said pad, and means for moving said support on said carrier adjacent said station.

29. A machine of the character described, comprising, a carrier arranged for movement relative to a station, means for moving said carrier,

a shoe support, a sole-engaging pad and a work holder on said support, said support and its co-operating parts being mounted on said carrier for unitary movement relative thereto, and means for effecting release of said pad and holder adjacent said station.

30. A machine of the character described, comprising, a carrier arranged for movement relative to a station, means for moving said carrier, a work support mounted on said carrier, a sole-engaging pad and a shoe holder on said support, means for effecting release of said pad and holder, and means for moving said support on said carrier adjacent said station.

31. A machine of the character described, comprising, a carrier arranged for movement relative to a station, a work support mounted for relative movement on said carrier and to a position adjacent said station, said work support having means thereon for sustaining a shoe and its sole in cooperative setting relation, including a work holder on said support, and means at said station adapted to release said work holder when the carrier is at rest.

32. A machine of the character described, comprising, a carrier arranged for movement relative to a station, a work support having means thereon for sustaining a shoe and its sole in cooperative setting relation including a work holder, said support with its holder being mounted on said carrier for unitary movement relative thereto and to a position adjacent said station, and means at said station adapted to apply said work holder.

33. A machine of the character described, comprising, a carrier arranged for movement relative to a station, a work support permanently mounted for relative movement on said carrier to a position adjacent said station, an inflatable work-engaging pad on said support adapted to maintain a shoe and its sole in cooperative setting relation thereon, and means at said station adapted to control the inflation of said pad.

34. A machine of the character described, comprising, a carrier arranged for movement relative to a station, a work support mounted for relative movement on said carrier and to a position adjacent said station, a work-engaging pad on said support adapted to exert a positive pressure against and maintain a shoe and its sole in cooperative setting relation thereon, and means adapted to release the pressure of said pad without disturbing the adjustment of parts cooperating therewith as said support approaches said station.

35. A machine of the character described, comprising, a carrier arranged for movement relative to a station, a work support mounted for relative movement on said carrier and to a position adjacent said station, an inflatable work-engaging pad on said support adapted to maintain a shoe and its sole in cooperative setting relation thereon, means adapted to deflate said pad as said support approaches said station, and means at said station adapted to effect application of said pad.

36. A machine of the character described, comprising, a carrier arranged for movement relative to a station, a work support mounted for movement on said carrier and to a position adjacent said station, a work-engaging pad on said support adapted to maintain a shoe and its sole in cooperative setting relation thereon, means adapted to effect release of said pad as said support approaches said station, means at said station adapted to effect application of said pad.

tion adapted to effect application of said pad, and means at said station adapted to move said support adjacent thereto.

37. A machine of the character described, comprising, a carrier arranged for movement relative to a station, a work support mounted for movement on said carrier and to a position adjacent said station, means on and movable with said support adapted to maintain a shoe and its sole in cooperative setting relation thereon, and means at said station adapted to successively move said support adjacent thereto and release the work.

38. A machine of the character described, comprising, a carrier arranged for movement relative to a station, a work support mounted for movement on said carrier and to a position adjacent said station, means on and movable with said support adapted to maintain a shoe and its sole in cooperative setting relation thereon, and means at said station adapted to successively move said support adjacent thereto, release the work, apply the work holding means and move said support back on the carrier.

39. A machine of the character described, comprising, a carrier arranged for movement relative to a station, a work support mounted for movement on said carrier and to a position adjacent said station, said work support having means thereon for sustaining a shoe and its sole in cooperative setting relation, means for moving said carrier, and means at said station adapted to successively stop said carrier, move said support adjacent thereto, move the support back on the carrier and start the carrier.

40. A machine of the character described, comprising, a carrier arranged for movement relative to a station, a work support mounted for movement on said carrier and to a position adjacent said station, means on and movable with said support adapted to maintain a shoe and its sole in cooperative setting relation thereon, means for moving said carrier, and means at said station adapted to successively stop said carrier, move said support adjacent the station, release the work, apply the work holding means, move the support back on the carrier and start the carrier.

41. A machine of the character described, comprising, a carrier arranged for movement relative to a station at the rim of said carrier, and a shoe support pivoted on said carrier and normally disposed within the rim thereof but

swingable thereby and into a position adjacent said station.

42. A machine of the character described, comprising, a carrier arranged for movement vertically past a station at the rim of said carrier, and a shoe support mounted on said carrier to move laterally beyond its rim and adjacent said station.

43. A machine of the character described, comprising, a carrier wheel having a rim arranged for movement vertically past a station, and a shoe support pivoted on said rim to swing laterally beyond its rim and adjacent said station.

44. A machine of the character described, comprising, a carrier arranged for movement relative to a station at the rim of said carrier, and a series of shoe supports permanently mounted on said carrier and normally retained within the rim thereof but successively movable therebeyond into position beyond its rim and adjacent said station.

45. A machine of the character described, comprising, a carrier wheel having a rim arranged for movement vertically past a station, and a series of shoe supports pivoted on said rim to swing laterally beyond its rim and in succession adjacent said station.

46. A machine of the character described, comprising, a carrier arranged for movement relative to a station at the rim of said carrier, and shoe supports mounted on opposite sides of said carrier to move beyond its rim and adjacent said station.

47. A machine of the character described, comprising, a carrier wheel having a rim arranged for movement vertically past a station, and shoe supports pivoted on opposite sides of said rim to swing laterally beyond its rim and adjacent said station.

48. A machine of the character described, comprising, a carrier arranged for movement relative to a station, and a series of shoe supports alternating on opposite sides of said carrier to move adjacent said station.

49. A machine of the character described, comprising, a carrier wheel having a rim arranged for movement vertically past a station, and a series of work supports pivoted in alternating relation on opposite sides of said rim to swing laterally adjacent said station.
